(57) **CLAIM**

The ornamental design for a rosary device, as shown and described.

DESCRIPTION

FIG. 1 is a perspective view of a rosary device;

FIG. 2 is a front view thereof;

FIG. 3 is a back view thereof;

FIG. 4 is a side view thereof;

FIG. 5 is an opposite side view thereof; and,

FIG. 6 is a top view thereof.

In FIG. 1, the broken line showing of environmental structure for purposes of illustrating the rosary device in a condition of use. The broken lines and the structure they depict form no part of the claimed design.
